UNITED STATES PATENT OFFICE.

WILLIAM M. BRUNST AND RALPH H. GREEGOR, OF COLUMBUS, OHIO, ASSIGNEES TO
THE KINNEAR MANUFACTURING COMPANY, OF COLUMBUS, OHIO, A CORPORATION
OF OHIO.

FIRE-RESISTING CURTAIN.

Application filed May 19, 1923. Serial No. 640,263.

The primary object of this invention is to provide an improved construction in which the normal effect of a curtain counterbalancing spring is rendered inoperative by the action of another spring which may be called a neutralizing or closing spring. A further object of the invention is to provide a flexible or winding connection between said neutralizing spring and the counterbalancing member. Other objects will appear from the following disclosure.

The invention is embodied in the example herein shown and described, the features of novelty being finally claimed.

15 In the accompanying drawing—

Figure 1 is a longitudinal sectional view through the curtain winding barrel.

Fig. 2 is a view of the left hand end of what is shown in Fig. 1 illustrating the 20 releasing and braking means.

Fig. 3 is a cross section on the line III—III Fig. 1, showing the position of the flexible connecting means when the curtain is unrolled.

25 Fig. 4 is a cross section showing the flexible member and its drum, the flexible member being wound up as when the curtain is in fully raised position.

Fig. 5 is a cross section of the winding 30 barrel on the line V—V Fig. 1.

In the views 6 and 7 designate the right hand and left hand end brackets, respectively, for supporting the curtain winding barrel 9 and its mechanism. 10 designates an 35 adjusting shaft fixable by means of wheel 10^a and member 10^b to the right hand bracket, said shaft also having pinned to it within the barrel a collar 11 to which is attached one end of a counterbalancing 40 spring 12. The other end of said spring is connected to hollow shaft or sleeve 13 supporting the other end of the barrel in the bracket 7. Extending loosely through said sleeve 13 is another shaft or rod 14 to which is connected one end of the neutralizing 45 spring or tension member 15, the other end of said spring being connected with the collar 11 before referred to. The coil spring 15 opposes the spring 12 when the 50 shaft of the latter is automatically released and the counterbalancing effect of the spring 12 on the curtain is then negated sufficiently to permit the curtain to unroll or close by gravity. It will be noted that the 55 counterbalancing effect of the spring 12 on

the curtain is obtained by pressure of the lug 21 on lug 22 and that the measure of such counter-balancing effect is changed by the relief of the pressure of lug 21 on lug 22 when the spring 15 is released by the release of shaft 14 in case of fire.

The shaft 14 has loose on it at its outer end an escapement wheel 16 and the outer end of the shaft 14 has pinned to it a wheel 17 having several sockets in its rim, any of which can be engaged by pins 18 extending through lugs on the escapement wheel to adjust the tension of the neutralizing spring 15. The springs 12 and 15 are of contrary winds or tension so that when the spring 15 is released as in case of fire the counterbalancing tension of spring 12 is negatived and the curtain will descend by gravity.

Secured by a key 19^a to the outer end of the sleeve 13 between the escapement and 75 end bracket is a drum 19 containing a tape 20 wound in volute fashion, said tape having one of its ends secured to the wheel 16 and its other end secured to said drum so that when the curtain is raised and lowered 80 the tape is coiled and uncoiled respectively. This tape is preferably of phosphor bronze. When the tape is wound up tightly as shown in Fig. 4 the curtain is in its uppermost position. The tape is made of sufficient 85 length to permit the full unwinding of the curtain without straining the tape or its fastenings in the contrary direction.

Contact between the sleeve 13 and the barrel is effected by means of a lug 21 on 90 said sleeve 13 and a lug 22 on the inner side of the head or plug 23, said plug being fixed in the end of the barrel as best seen in Fig. 5.

The escapement wheel 16 in connection 95 with an oscillating frame 24 pivoted on pin 24^b carrying spring held teeth 24^a to alternately engage the teeth of said wheel serves to retard the descent of the curtain when released for closing. The escapement wheel is 100 held from movement by the engagement of one of the teeth 24^a of the oscillating frame 24 with the wheel by means of a lever 25 having a tooth 26 to engage a tooth 27 on the said oscillating frame 24; and said lever 105 25 can be held up with the parts so engaged by means of another latching lever 28, such as commonly used in such constructions, pivoted at 28^a and releasably sustained by means of a wire 29 containing a fusible member 29^a 110

fastened to a fixed point as usual or in any suitable manner to effect the automatic release of lever 25 in case of fire. When in the event of fire the escapement wheel 16 is 5 automatically released the rotation of that wheel as viewed in Fig. 2 is anticlockwise.

It will be observed, therefore, that normally the counterbalancing spring 12 permits the curtain to be drawn down and held 10 in the place to which drawn because as the curtain is drawn down the said spring is proportionally wound up and placed under sufficiently increased tension to counterbalance the unwound portion of the curtain. 15 This in itself is very common practice and well understood in the practical art. But as before stated the effect of the counterbalancing spring 12 is designed to be offset or negatived by the spring 15 when the curtain is 20 automatically released, that is when the lever 25 and its lug 26 is dropped away from the tooth 27 thereby releasing the shaft 14 and permitting the curtain to unwind by gravity, the escapement mechanism acting as a brake 25 to prevent a violent descent of the curtain.

The operation which can be gathered from the foregoing is as follows: To adjust the tension of the spring 12 so that it will amply counterbalance the curtain in any of the 30 positions to which it is unrolled that spring is placed under tension as far as necessary for that purpose by turning the shaft 10 with the member 10^a and fixing the latter to the lug on the end bracket 6 by the pin 10^b as shown. The spring 15 which is of contrary effect to spring 12 is then placed under tension by turning the shaft 14 with the wheel 17 until enough tension is stored therein so that when released it will counteract sufficiently the effect of spring 12 to permit the curtain to unroll by gravity upon the release of the escapement or braking wheel 16 it being remembered that said escapement wheel is still connected by pin 18. In this 40 preparation the escapement wheel is locked from rotation by raising the lever 25 and securing it with the lever 28 and wire 29 containing fusible link 29^a as described. These 45 preparatory steps are performed while the curtain is rolled up on the barrel 9 and the flexible member 20 wound up. As long as the parts are in the positions just described the curtain can be unrolled or rolled up by hand or otherwise to any position desired 50 and left, because of the counterbalancing spring 12. When the barrel 9 and the part 19 are turned in the curtain unrolling direction the spring 12 is wound tighter by reason of the pressure of the lug 22 on the lug 55 21, this operation placing said spring 12 under progressively increased tension to sustain the unwound portion of the curtain to support it where left. When the curtain is 60 raised by hand or otherwise the spring 12 65 is proportionately released thereby diminish-

ing its counterbalancing tension and in this operation the lug 21 follows the lug 22 as the barrel turns. When the curtain is raised the flexible strap 20 is wound up (see Fig. 4) and conversely when the curtain is lowered said strap is unwound (see Fig. 3).

Assuming therefore that the curtain is in the coiled up or in a partially coiled state and the heat of a fire melts the fusible link 29^a the latch 26 will be released from the tooth 27 and the ring 24 will oscillate back and forth first permitting the shaft 14 to turn and the spring 12 to be deprived of or reduced in its counterbalancing twist and effect on the curtain. In this operation the 70 spring 15 acts against spring 12 through the medium of parts 17, 18 and 16, the last being connected to drum 19 by the tightly wound tape 20, the part 19 being keyed to sleeve 13 which holds one end of spring 12. 75 Because the spring 12 in this last operation loses some or all of its counterbalancing effect the curtain is free to drop by gravity. The pull of the curtain by gravity not only starts the oscillations of the ring 24 but 80 keeps up said operation until the curtain closes the opening for which it is designed. The pull of the curtain operates the escapement wheel somewhat as the main spring 85 of a watch starts and keeps up the operation of the escapement. Upon the release of the shaft 14, as in case of fire, the flexible member does not unwind because the sleeve 13, drum 19 and wheel 16 all rotate together. The oscillation of the ring 24 with its dogs 90 24^a on the ratchet 16 serves intermittently to resist or prevent such a rapid or violent descent of the curtain and its impact on the sill or floor as would endanger its integrity 95 and the parts and connections cooperating 100 with it.

In practice it will be observed that our invention makes it possible to manually operate the curtain to raise and lower it to any desired position without affecting the successful operation of the spring for negating the effect of the tension member on the counterbalancing spring and the release of the curtain for closing the opening in the event of fire. Upon the release of the spring 110 15 the tension of the counterbalancing spring 12 is diminished by the pressure of stop 21 on stop 22 thereby permitting or causing the curtain to unroll.

The forms of the parts can be changed 120 without departing from the gist of the invention as claimed.

What we claim is:

1. In a fire resisting rolling curtain, the combination of a curtain winding member, 125 a counterbalancing member for the winding member, a tension member for negating the effect of the counterbalancing member, flexible winding means connecting the tension member and counterbalancing member 130

and limiting the curtain coiling movement of the winding member, means for holding said tension member inert upon the counterbalancing means and thermally controlled 5 means for releasing said tension member.

2. In a fire resisting rolling curtain, the combination of a curtain winding member, a counterbalancing member for the winding member, a tension member for negativ- 10 ing the effect of the counterbalancing member, means whereby said tension member may be adjusted and fixed in adjusted position with reference to said counterbalancing member, flexible winding means connecting the ten- 15 sion member and counterbalancing means for limiting the curtain coiling movement of the winding member, means for holding said tension member inert upon the counterbalancing means and thermally controlled 20 means for releasing said tension member.

3. In a fire resisting rolling curtain, the combination of a curtain winding member, a counterbalancing member for the winding member including a sleeve movable ro- 25 tarily with reference to the winding member, a stop for limiting the movement of said winding member with reference to the sleeve, a spring for negativ- 30 ing the effect of said counterbalancing member, a shaft connected with said spring, flexible means connecting said shaft and sleeve, said flexible means adapted to limit the coiling of the curtain on said winding member, means for holding said shaft, and thermally controlled means 35 for releasing said shaft.

4. In a fire resisting rolling curtain, the combination of a curtain winding member, a curtain counterbalancing member, a tension member for negativ- 40 ing the effect of the counterbalancing member, a sleeve connected with the counterbalancing member and adjustable with reference to said tension member and winding member and a flexible connection between said sleeve and tension mem- 45 ber.

5. In a fire resisting rolling curtain, the combination of a curtain winding member, a counterbalancing member, a tension member for negativ- 50 ing the effect of the counterbalancing member, a sleeve connected with the counterbalancing member and adjustable

with reference to said tension member and winding member and a flexible connection between said sleeve and tension member, said flexible connection consisting of a tape 55 volutedly wound.

6. In a fire resisting rolling curtain, the combination of a curtain winding member, a curtain counterbalancing member, a tension member for negativ- 60 ing the effect of the counterbalancing member, a sleeve connected with the counterbalancing member and adjustable with reference to said tension member and winding member, a flexible connection between said sleeve and tension member 65 and thermally controlled means for restraining the operation of the tension member.

7. In a fire resisting rolling curtain, the combination of a curtain winding member, a curtain counterbalancing member, a tension member for negativ- 70 ing the effect of the counterbalancing member, a sleeve connected with the counterbalancing member and adjustable with reference to said tension member and winding member, a flexible connection between said sleeve and tension member 75 and means for braking said sleeve.

8. In a fire resisting rolling curtain, the combination of a curtain winding member, a curtain counterbalancing member, a tension member for negativ- 80 ing the effect of the counterbalancing member, a sleeve connected with the counterbalancing member and adjustable with reference to said tension member and winding member, a flexible connection between said sleeve and tension member 85 and thermally controlled means for releasing said sleeve and means for braking said sleeve.

9. In a fire resisting rolling curtain, the combination of a curtain winding member, counterbalancing means for the curtain, a tension member for negativ- 90 ing the effect of said counterbalancing member, a sleeve connected with the counterbalancing member 95 connected with said tension member, means for limiting the movement of said sleeve with reference to the winding member, and a flexible connection between said sleeve and tension member.
